PROCESS AND APPARATUS FOR CONDITIONING THE SURFACES OF METAL BODIES

Arthur M. Keller, Livingston, James H. Bucknam, Cranford, and Alfred J. Miller, Garwood, N. J., assignors to The Linde Air Products Company, a corporation of Ohio

Application May 11, 1940, Serial No. 334,510

20 Claims. (Cl. 148—9)

This invention relates to blowpipe apparatus for thermally conditioning the surfaces of ferrous metal bodies and more particularly to blowpipe apparatus for thermochemically removing a layer of metal from the entire bottom surface of a steel body such as a billet, bloom, slab, or the like, to apparatus for removing scale from such surfaces and to a process of conditioning a surface of such metal body.

In the casting of steel ingots and during the hot rolling of steel, defects such as scale, cracks, seams, slag-inclusions and the like form on and in the surfaces of the steel bodies and cause imperfections in the finished rolled products. In order to reduce the number of rejections of finished rolled products, the surface defects are generally removed before or during an intermediate stage of the rolling. Scale is commonly removed by pickling and other defects have often been removed by mechanically cutting or chipping away the defective surface metal. Hand-operated blowpipes, commonly referred to as hand-deseaming blowpipes, are now also used for thermochemically removing the defective surface metal adjacent each defect by effecting the combustion of the steel with oxygen. Recently, machines employing suitable blowpipe means have come into use for simultaneously thermochemically conditioning an entire surface of billets, and the like, or for simultaneously conditioning two opposite, substantially vertical side faces of such billets or for conditioning the top surface of slabs and the like. These machines may be used for conditioning steel shapes, either when cold or while they are at a rolling temperature and are passing from one roll stand to another such as is commonly employed in a steel mill.

The present invention provides an apparatus for thermally conditioning the surface of a steel body such as a bloom or slab or for eliminating scale, and more particularly a machine for thermochemically removing a layer of surface metal from the entire bottom surface of the body during a single pass, preferably while the steel body is moving along a roll table from one rolling operation to another. A multiple nozzle blowpipe head producing high-temperature preheating flames and a composite sheet-like oxygen stream substantially equal in width to the surface of the slab is maintained in contact with the work surface during relative longitudinal movement between the head and slab in order that a substantially uniform depth of metal may be removed and the gas efficiently used. The operat-

ing mechanism is so arranged and constructed that the head is pressed upwardly into contact with the bottom slab surface at a substantially uniform pressure irrespective of changes in the level of the surface and irrespective of any warp or twist of the slab. The head may be raised to or lowered from the operating position adjacent the work and the machine may be moved transversely out from under the conveyor line

10 whenever desirable.

Desurfacing the bottom surfaces of slabs instead of the top surface has been found to present numerous advantages; the molten slag does not flow over the edges to form undesirable fins; 15 the slag quickly falls away from the bottom surface and does not tend to pile up or collect in front of the nozzles and clog the nozzles or form deposits on the surface; the disposal of the slag which falls away from the bottom surface does not involve the considerable difficulties which are involved in the disposal of the slag which pours over the trailing end of the slab when removing metal from a top surface; the bottom surface is always at the same level except for a 20 relatively small change of level caused by deformation of the slab, whereas, when desurfacing the top surface, the level of the upper surface varies according to the thickness of the slab; and, the desurfacing machine may be more 25 economically supported.

Accordingly, the principal objects of this invention are to provide improved procedure and apparatus for surface conditioning the entire bottom surface of a metal body; to provide such 30 process and apparatus particularly adapted for removing a layer of surface metal from the bottom surface of a ferrous metal body, while such body is at a rolling temperature and at a point between successive rolling operations; to provide such an apparatus which may be installed beneath an existing conveyor table of a steel mill; to provide a raising and lowering mechanism for resiliently supporting the blowpipe head, for urging the blowpipe head upwardly 40 against the lower surface of the body with a constant pressure, and for maintaining the blowpipe head in uniform contact with the steel body irrespective of the warp or twist of the body; to provide such apparatus which includes means for lowering the gas delivering unit before reaching the end of the steel body to prevent damage thereto by irregularities such as "rosebuds" or other irregularities at the end of the steel body; to provide such apparatus which includes means for retaining the steel body on the 45 50 55

roll table rollers irrespective of the upward pressure exerted by the gas delivering unit; to provide such apparatus which will eliminate the considerable difficulties of the slag disposal when desurfacing relatively large steel slabs; to provide such apparatus which includes an improved, water-cooled shoe for contacting the surface of the steel body to maintain the blowpipe nozzles in operative relation to the surface and for protecting the blowpipe nozzles; and to provide a process for conditioning the surface of a metal body wherein the means for applying the gas is moved away from the body before the end of the body is reached and the flow of gas is continued to prevent slag adherence thereto.

These and other objects and novel features of this invention will become apparent from the following description taken in connection with the accompanying drawings, in which:

Fig. 1 is a side elevational view of a desurfacing machine embodying the principles of the present invention and installed beneath a roll table of a steel mill;

Fig. 2 is a front elevational view of the desurfacing machine of Fig. 1;

Fig. 3 is a plan view of the machine of Fig. 1 with portions broken away more clearly to disclose the construction;

Fig. 4 is a fragmentary view of the front of the hold-down means taken along line 4-4 of Fig. 1;

Fig. 18 is a fragmentary rear view of the desurfacing machine to show the means for turning on and off the preheat gases;

Fig. 19 is a wiring diagram schematically illustrating the electrical circuit of the control means for operating this machine; and,

Fig. 20 illustrates the sequential operation of the drum-type switch controller.

Referring to the drawings and particularly to Figs. 1, 2, and 3, the body to be surface conditioned may be a ferrous metal body such as a relatively wide steel slab S supported on the usual rollers 20 of a steel mill conveyor table C. The rollers 20 are mounted on axles supported in suitable bearings and the axles are connected through bevel gearing to the longitudinal drive shaft 21 which is driven by a motor in the usual manner, the gearing and motor are not shown in the interests of greater clearness of the drawing. The surface conditioning head shown generally at H is substantially equal in width to the widest steel body to be surface conditioned and is attached to and supported by the carrier plate 23 which will be later described in detail. The head H and carrier plate 23 are resiliently supported by and moved up and down by two air cylinders 25 cradled on the frame of a motor driven carriage F mounted on transverse rails R for movement into and out of operative alignment beneath the conveyor table C. The rails R may be fastened to the floor of the steel mill or to any suitable supporting base beneath the roll table C. The slag formed by the thermo-chemical removal of the surface material is collected in the hopper W, disposed beneath the slab S, and the hopper W will be later described in more detail.

The box-like frame of carriage F comprises two relatively long parallel side members 26 which are rigidly spaced apart by cross-members 27. Near the right-hand end of members 26 there is secured to plates 26 a transverse upwardly extending plate 28. An upwardly extending left-hand plate 29, similar to plate 28, is also secured between the members 26. Secured to side members 26 and plate 28, are a pair of upwardly extending front and rear plates 30 and a similar pair of front and rear plates 31 are secured to side members 26 and to the upwardly extending plate 29. Plates 30 and 28 form the partially enclosed right-hand guide column J, and plates 31 and 29 form the left-hand guide column J'. The top of the columns J and J' may be closed by covers 32 to protect the mechanism therein from dirt and other foreign materials.

The carriage F is supported on the rails R by four wheels 33 which are mounted on the outer ends of two transverse axles 34 (Fig. 6), extending through plates 31 and through side members 26. The axles 34 are mounted in bearings 35 secured against the outside faces of members 26. The wheels 33 are protected against dirt, dust and slag by covers 36 fastened to members 26. Only the left-hand axle 34 is motor-driven and to this end there is mounted centrally thereon a worm gear 37 which meshes with a worm 38, formed integral with or mounted on a shaft 39, supported by bearings 40 in the cross-members 27 (see Figs. 5 and 6). The shaft 39 is connected to the output shaft of a speed reducer 41 of a motor unit 42 by a flexible coupling 43 (Fig. 3). Motor 42 supplies the motive power for moving the surface conditioning machine along the rails R to a position beneath the roll table C or to a position out of operative alignment with the roll table. An electrical solenoid-operable brake shown generally at B is mounted in the frame F and when the electrical circuit to the motor 42 is closed to energize the motor, the solenoid of brake B is energized so that the brake does not

engage the rearwardly extending portion of the motor shaft but when the electrical circuit is broken the jaws of the brake B grip the motor shaft and prevent the desurfacing machine from moving from its position.

Referring more particularly to Figs. 1 to 3 and 7, the surface conditioning head H is mounted on the upper ends of two piston rods 24 of the air cylinders 25 and is supported and moved upwardly and downwardly by the pistons operating in the cylinders 25. On cross members 27 there are three bearings 44 in which are pivotally mounted outwardly extending and axially aligned trunnions 45 of two cradle members 46. The cradle members 46 are therefore rockable about a horizontal transverse axis. The front member 26 may be cut away as more clearly shown in Fig. 2 to allow cradle members 46 to rock forwardly. Each of the two air cylinders 25 has a pair of trunnions pivotally mounted in bearings 47 on cradle members 46. The axes of the bearings 47 are perpendicular to the axis of the cradle trunnions. Thus each air cylinder 25 and cradle member 46 can tilt fore and aft in bearings 44 and each air cylinder 25 individually can tilt to the left or right in bearings 47. When air is admitted under pressure to the head ends of cylinders 25 and under the pistons therein, the surface conditioning head H is raised, and when the air pressure is released the head H is lowered due to its weight.

On the upper end of each piston rod 24 there is fastened a clevis 48 which is pivotally secured to a horizontal pin 49, (Fig. 7) by a transverse pin 50. On the carrier plate 23 of the head H there are two pairs of depending brackets 51 and in each pair of brackets one of the horizontal pins 49 is pivotally mounted so that the carrier plate is tiltable relatively to the piston rods 24 both fore and aft and laterally.

Guiding means are provided in right and left columns J and J' for normally maintaining the surface conditioning head H in a vertical position but allowing the head to tilt or cant to the right or left to follow the surface of a twisted or warped slab. As both guide columns are the same except that one is left-hand and the other right-hand, only one will be described in detail. To each end of the carrier plate 23 there is fastened a bracket member 53. The right-hand bracket member 53 extends into the guide column J, as more clearly shown in Figs. 8 and 9, and has pivotally mounted thereon seven rollers which contact vertical guide members in column J.

In column J there are four vertical guide members 54, 55, 56, and 57. Mounted on horizontal pins 58 in member 53 extending transversely from the upper and lower corners thereof are a pair of rollers 59 which may contact either a guide surface 60 or 61 of the guides 54 and 55, respectively. The guides 54 and 55 coact with the similar guides in guide column J' to hold the carrier plate in the vertical position with respect to fore or aft deflection. The distance between the guide surfaces 60 and 61 is slightly greater than the diameter of rollers 59 to lower the friction and work required to raise the surface conditioning head H. By adjusting screws 52 extending inwardly through the plates 30 the guides 54 and 55 may be moved to adjust the distance between the guide surfaces 60 and 61. Also mounted intermediate between and perpendicularly with respect to pins 58 in member 53 is a pin 62 on the outer end of which is mounted a

roller 63 which contacts an edge guide surface 64 of the guide member 54. A similar roller in the guide column J' contacts a similar guide surface to prevent any transverse shifting of the head H either to the left or right. The bracket 53 also carries horizontal upper and lower pins 65 and 66, which are axially parallel to pin 62 and on each end of which there is mounted a roller 67 and 68, respectively. The front rollers 68 are arranged to contact the guide surface 71 of member 56 and the rear rollers 68 may contact the guide surface 73 of member 57. Neither the upper or lower pairs of rollers 67 and 68 will normally contact their respective guide surfaces when the head H is in the upright horizontal position.

Roller 63 is vertically midway between the upper and lower rollers 68 and the upper and lower rollers 59. As the left-hand end of the carrier plate and the left-hand column J' are similar to the corresponding right-hand units, the head H cannot shift horizontally either to the left or right but can tilt or cant either to the left or right until the lower or upper pairs of rollers 67 and 68 contact the guide surfaces 71 or 73. Thus, the desurfacing head H can tilt to follow the lower surface of twisted, warped or bent slabs. The row of blowpipe nozzles in head H is always substantially parallel with the bottom surface of slab S so that a substantially uniform depth of metal is removed from the entire surface irrespective of surface inclination or slab warpage.

The carrier plate 23 may be fabricated by welding together preformed plates or may be formed by other suitable means to provide a member which is light in weight but of a rigid construction. The carrier plate is disposed below the slab and is not subject to as intense a degree of heat as it would be if disposed above the slab, but, it is preferable that the carrier plate be water cooled to prevent damage or warpage by heat. Carrier plate 23 is therefore provided with a chamber 72 having an inlet connection 69 (Fig. 2) through which cooling fluid is admitted to the chamber 72. The cooling fluid is discharged through two outlet connections 74 at each end wall and to the drain pipe 78.

As shown by the drawings, the desurfacing head H comprises a number of similar blowpipe heads 75, each containing a plurality of nozzles and means for supplying each head with suitable gases and cooling fluid. As all of the heads are similar, only one multiple nozzle head will be described in detail.

Each head 75 comprises a nozzle retaining or header block 76 and a removable nozzle protecting shoe 77. The head 75 is removably attached to the carrier plate 23 by bolts 79 and 79'. A clamp bar 80 may be placed between the heads of bolts 79 and the head 75 as shown and, if only part of the bolts 79 are tight the head 75 still is retained securely in place. In the block 76, there is a plurality of similar oxidizing gas passages 82 each of which is enlarged and threaded at its forward outlet end to operatively receive the inlet end of a nozzle 81 removably secured therein by means of a nozzle retaining nut 83. The inlet end of the passage 82 communicates with a chamber 84 formed in block 76 there being a chamber 84 for each two passages 82. The inlet end of each chamber 84 is adapted for receiving the threaded end or connection of the oxidizing gas supply tube 85 which in turn communicates with a source of oxidizing gas. The oxidizing gas flows from each supply tube 85, through dis-

tributing chamber 84, the two oxidizing gas passages 82 and through the central oxidizing gas bores of the two nozzles 81 secured in block 76. Tubes 85, passages 82 and chambers 84 are duplicated in each block 76 so that all of the nozzles in each head 75 are supplied with oxidizing gas such as oxygen. Each tube 85 contains a manually operable valve 86 for controlling the flow of oxidizing gas to two nozzles 81.

The outlet end of each passage 82 is also formed with a pair of seats which coact with seating surfaces on the nozzle 81 to form gas tight seals. Between these seating surfaces the cavity in the block 76 is formed larger than the nozzle to provide the usual combustible or preheat gas distributing chamber at 88 for distributing a combustible gas mixture, such as oxygen and acetylene to the preheat passages in the nozzle. As disclosed in Fig. 16, a plurality of passages 89 may be drilled in the block 76 each communicating with a chamber 88. The passages 89 are so drilled that the inlet ends of each pair of passages intersect at the outlet end of one of the passages 90. The outer ends of passages 89 may be plugged with silver solder or other suitable means. The inlet end of each passage 90 is adapted to receive the threaded end of the blowpipe tube 91 of the blowpipe 92. The combustible gas is mixed in the blowpipe and flows through tube 91, passage 90, the two passages 89 into the two chambers 88 and from each chamber 88 to the preheating passages of each corresponding one of the nozzles 81. For each pair of nozzles 81, there is provided a separate blowpipe 92, a passage 90 and two passages 89.

The shoe 77 is attached to the block 76 by bolts 94 and 95 as more clearly shown in Figs. 13 and 14. The bolts 94 extend through the shoe 77 and threadedly engage block 76. Bolts 95 are inserted from the rear of block 76, and extend through one of the cooling chambers 105 and threadedly engage the shoe 77. To prevent leakage of cooling fluid from the chamber past bolt 95, a sealing or packing sleeve 93 is provided. A gasket 87 may be provided between shoe 77 and block 76 to prevent leakage of cooling fluid therebetween. Each nozzle 81 is retained in the block 76 by its nut 83. The forward end of each nozzle extends through a hole 96 in the front wall of the shoe 77 and the forward end of the nozzle is substantially flush with the outer wall of the shoe. To prevent cooling fluid from leaking past the nozzle 81 to the outside of the shoe, a packing ring 97 which encircles the central portion of the nozzle is pressed against the inner front wall surface of shoe 77 by a compressed spring 98 surrounding the nozzle. Each nozzle is retained in the head 75 by similar means, but because of lack of space, the end nozzles in each head 75 are provided with slightly different packing as shown in Fig. 15. The end holes 96 are enlarged at approximately the central portion and contain a packing ring 100. The packing rings 100 fit the outer walls of the end nozzles tightly enough to prevent leakage of fluid past the nozzles. If there is enough space, the end nozzles could be packed in the same manner as the other nozzles.

With this construction of the blowpipe head, the nozzles of each head 75 may be readily removed, all or singly, for replacement or inspection. By removing bolts 94 and 95, the shoe 77 may be readily removed to expose the nozzles, which are individually removable. Therefore, the head 75 may be readily dismantled, repaired

and assembled. By loosening bolts 79, the head 75 may be readily removed as a unit for repair or replacement.

The heads 75 are in contact with the bottom surface of a usually hot slab and are in a zone of high temperature heat from the slab, the pre-heating flames, the heat of the reaction and the hot slag. While the heads 75 are not exposed to as much heat as they would be if positioned on top of the slab, the heads and nozzles must be adequately cooled to prevent overheating. Each block 76 is adapted to receive a water inlet connection 103, and is formed with two transverse chambers 104 and 105 and is also formed with a cavity which coacts with a cavity in the shoe 77 to form the relatively large cooling chamber 106. A passage 107 connects the inlet 103 and chamber 104; passage 108 provides communication between chambers 104 and 106; and passage 109 provides communication between chambers 106 and 105. In the block 76 there is a bore 112 adapted to receive the threaded connection 113 having attached thereto a length of overflow tubing 114 which extends from connection 113 through bore 112 to substantially the top of chamber 105. Cooling liquid, such as water, flows from a supply tube 101, which is connected to a suitable source of supply, through connection 103, passage 107, chamber 104, passage 108, chamber 106, passage 109, into chamber 105 and out the overflow tube 114 and through connection 113 and tube 115 to the drain pipe 78. The cooling fluid chambers and connecting passages are so arranged that all portions of the head and nozzles are adequately cooled. The central portions of nozzles 81 are completely surrounded by cooling fluid and the gas passages 90 and 82 are well cooled to prevent overheating and possible pre-ignition of the combustible gas mixture. By having the inlet end of overflow tube 114 positioned at the top of chamber 105, the chambers of the head are always maintained full of cooling fluid. The forward or front face of the nozzles 81 are exposed to the heat but otherwise are fully enclosed.

The number of nozzles in a head may be any convenient number but as herein shown and described, each head 75 comprises a nozzle head or block 76, a shoe 77, eight nozzles 81, four blowpipes 92 for supplying mixed combustible gas, four oxygen supply lines 85, a fully enclosed cooling system, and the necessary valves for controlling the flow of the gases and cooling fluid. The nozzles in each blowpipe head and the end nozzles in adjacent heads are so spaced that the individual oxygen streams from the nozzles intermingle so as to direct a substantially sheet-like stream of oxygen onto a transverse zone extending completely across the surface of slab S. The surface of shoe 77 which contacts the slab is subject to damage by abrasion, and to protect the shoe, ridges of metal 116 which are resistant to abrasion at high temperatures may be deposited on the slab contacting surface. Additionally to increase the useful life of the head 75, a layer of abrasion-resistant material may be deposited on the shoe 77 and block 76 as is shown generally at 117 and 118, respectively. As shown in Figs. 13 and 14, the shoe 77 overlaps the forward corner of the block 76, as indicated at 119, so that any force or shock on shoe 77 is taken by the block 76 and shoe 77 will not shift and damage the nozzles.

Across the back of the surface conditioning machine there is fastened a relatively large cutting

oxygen pipe 120 (Fig. 7) from which lead eight cutting oxygen lines 121. There is a line 121 for each head 75 and the flow of cutting oxygen to each head may be controlled either by the manually operable valve 122 or the solenoid controlled valve 123 in each line 121. Each oxygen line 121 is connected to an oxygen header 125 from which lead four lengths of tubing 126, each of which is connected to one of the four tubes 85, each tube 85 containing a manually operable valve 86. The preheat fuel gas, such as acetylene, flows by means of suitable lengths of pipe from one of the four acetylene supply lines 127 through one of the four corresponding acetylene valves 128 to a pair of manually operable valves 129. To each of the valves 129 there is connected a length of flexible tubing 130 which in turn is connected through a suitable length of pipe and hose connection to an acetylene header 131. Four lengths of copper tubing 132 lead from acetylene header 131 and each length of tubing contains a manually operable valve 144 and is connected to one of the four blowpipes 92. Similarly, the preheat oxygen supply line 133 by means of suitable piping communicates with the four valves 134 and each valve 134 is connected to two manually operable valves 135 each of which is connected through a suitable length of tubing 143 to a preheat oxygen header 136. Each of the four lengths of copper tubing 137 communicate through a manually operable valve 140 with the header 136 and with one of the blowpipes 92 to supply preheat oxygen thereto.

Also across the back of the machine are the cooling liquid supply and drain pipes 138 and 139. Supply pipe 138 is connected to a source of constant temperature cooling liquid such as water and water flows from pipe 138, through a valve 124, flexible hose 141 and the length of copper tubing 142 to one of the blowpipes 92. The blowpipes 92 are connected by short lengths of tubing 145 and cooling water flows from one blowpipe to the next through tubes 146. Cooling water flows from the last blowpipe in each head through a length of tubing 146, hose connection 147, hose 148, valve 149 and out through the drain pipe 139. The water for cooling the blowpipes is preferably heated to a low constant temperature so as to be at a constant temperature and not vary with the weather or temperature of the surrounding atmosphere, as would unheated water. The cooling liquid supply pipe 150 supplies cooling liquid to the heads 75 and carrier plate 23. The supply pipe 150 communicates through a manually operable valve 151 and a flexible hose 102 with supply tubes 101 of each head 75. Cooling water flows from pipe 150 through valve 151, hose 102, tube 101, inlet connection 103 and through each head 75 and through the outlet line 115 to the drain 78. A pressure operated switch 150' may be connected to the supply pipe 150 so that when the pressure of the cooling water drops below a predetermined value the switch 150' will operate an alarm, such as ringing a bell or turning on a light, to indicate to the operator that the cooling water pressure is below a safe value and that there is an inadequate supply of cooling fluid. Switch 150' also may be so connected as to operate the preheat gas controlling means, which is described later, to turn off the preheat flames and/or may be so connected as to operate the head raising and lowering means, which is described later, to cause the head H to be lowered away from the slab S.

The gas, water, and air supply pipes which are mounted on the back of the machine are connected through lengths of flexible tubing 152 to 78

suitable sources of supply (see Fig. 2 and Fig. 3). The lengths of tubing 152 are flexible and of such a length as to allow the desurfacing machine to move along the rails R to a position beneath or to one side of the roll table. A supporting apron 153 is provided at the left-hand end of the machine to support the flexible supply tubing 152.

By means of the manually operable valves in the preheating acetylene and oxygen lines and in the cutting oxygen line, the nozzles may be blanked off in pairs, if for any reason it is desired to reduce the effective width of head H. Thus, when conditioning the surface of a slab which is narrower than the width of the head, the end nozzles may be blanked off in pairs by means of valves 140, 144, and 86 so the effective width of the head H is substantially equal to the slab. Normally, all manually operable valves are open and the flow of gases is controlled by electrically operable valves and the switch-means controlling all electrical operated valves may be conveniently located at a single point.

On the back of the machine there is positioned a relatively small air operated power cylinder 155 for each two heads (see Figs. 3 and 18). The piston rod 154 of each air cylinder 155 is connected to the valve levers of an acetylene valve 128 and a preheat oxygen valve 134 for controlling the flow of preheat gases to two heads 75. The air lines 156 and 157 communicate with the ports of the four-way solenoid valve 158 and communicate with the head and rod ends of air cylinders 155. Air under pressure is supplied to the four-way valve 158 and when an electrical circuit to this valve is closed to energize the solenoid, the valve 158 is so positioned that air under pressure is supplied to line 156 and to the head end of each air cylinder 155, to raise all the pistons and open all of the preheat gas valves 128 and 134. Simultaneously, the rod end of each air cylinder 155 and line 157 is opened to the atmosphere and, when the solenoid valve 158 is de-energized, air under pressure is admitted to line 157 and the rod ends of air cylinders 155 to close valves 128 and 134, and line 156 and the head ends of the air cylinders are opened to the atmosphere. The four-way valve 158 simultaneously opens and closes all of the preheat gas valves and the preheat gases separately flow to the blowpipes where the gases are mixed and the combustible gas mixture flows from the blowpipes to the nozzles, unless some of the gas lines are closed by means of the manually operable valves.

Suitable limit switches may be provided to prevent the desurfacing machine from moving too far along the rails R in either direction. It is essential that the desurfacing head H be correctly positioned beneath the slab S and as an aid in positioning the machine, a position indicator M is provided. On a machine there is mounted an indicator dial 160 (Fig. 2) having a pivotally mounted indicator pointer 161 which is connected by means of a pinion and rack to the vertical rod 162, positioned by suitable collars. On the lower end of rod 162 there is fastened a bracket 163 containing a roller 164 adapted for engaging the sloping surface of the adjustable cam 165. The cam 165 is positioned and proportioned so that as the machine approaches the correct position beneath the slab S, the rod 162 is raised and the indicator pointer 161 is moved through an arc across the dial 160 to indicate the position of the desurfacing machine relative to the slab. The operator, while positioned at one side of the machine out of the zone of intense

heat, can readily see the indicator M and ascertain whether or not the desurfacing machine is in the correct position relative to the slab S. As a further aid in positioning the desurfacing machine, a downwardly depending plate 167 may be provided on the carriage F. A stop 168 may also be provided and secured between the rails R so that when the machine reaches its limit of movement towards the right, plate 167 will strike the stop 168 and stop the machine.

On each of the columns J and J' there may be provided a limit switch 170 having an inwardly extending finger 171 and which is so positioned that as the head H is moved upwardly toward the bottom of the slab one of the rollers 59 will strike the fingers 171 to close the switches 170. When switches 170 are closed, the circuit to the four-way solenoid valve 158 is energized to turn on the preheat valves 128 and 134. The switches 170 can be set so that as the head H approaches the bottom of the slab the preheat gases are automatically turned on and lighted. It may at times be desirable to provide an electric delay device in the switch circuit so that the preheating gases will be turned on a short time prior to lighting, to purge the blowpipes and gas lines and prevent backfire which is very undesirable. In addition, the limit switches 170 are preferably positioned so as to turn the preheating gases off after the head H has been withdrawn downward a short distance from the surface of the slab to eliminate any possible chance of molten slag clogging the blowpipe nozzles.

Air under pressure is supplied from a suitable source to one of the flexible hoses 152 connected to the supply line 173 which is divided into two branch lines 174 and 175. Air line 174 is connected to the four-way valve 158 to supply air for operating the preheat gas valves. At a T connection 176, the air line 175 is split into two lines 177 and 178, each of which contains a pressure regulator 179 and a pair of manually operable valves 180 on each side of the regulators. The regulators 179 maintain the pressure of the air delivered to a common line 181 within fairly close limits and by means of the valves 180 either one of the lines 177 and 178 may be closed should one of the regulators become inoperative. A pressure indicator 182 may be provided to visually indicate the air pressure in line 181. Air line 181 is branched into two air lines 183 and 184. Line 183 has interposed therein the electrically-operable solenoid valve 185 which is operable through suitable switch means by remote control such as at a remote control table. When the electrical switch of valve 185 is closed, the solenoid of valve 185 is energized to open the valve against spring pressure which normally closes the valve when the solenoid is not energized and air under pressure flows from line 183 through valve 185, a line 186 and short lengths of flexible hose 187 to the bottom or head ends of cylinders 25, thereby raising the head H toward the slab S.

Branch air line 184 communicates with a large air receiver tank 189 and when solenoid valve 185 is energized by operation of its control switch to open the valve to admit air to cylinders 25, tank 189 also communicates with cylinders 25. The air tank 189 in effect increases the volume of the cylinders 25 so that if the pistons in the cylinders are displaced downwardly, as by irregularities in the surface of slab S, the pressure in cylinders 25 and tank 189 only varies

a slight amount and the pressure is not materially increased as it would be if tank 189 were omitted. A suitable safety valve 190 is operatively connected to tank 189 and is so constructed that it may be adjusted to open when the air pressure in tank 189 exceeds a predetermined safe pressure and to close or remain closed when the air pressure in tank 189 is below the predetermined safe pressure. If the pressure in tank 189 surpasses a predetermined value, safety valve 190 automatically opens and air is exhausted to the atmosphere through the vent tube of valve 190 and, when enough air has been exhausted from tank 189 so that the pressure in tank 189 is at or slightly below the predetermined value, safety valve 190 automatically closes. Thus, the pressure in tank 189 is maintained within safe limits. A normally open, electrical solenoid operated, relief valve 191 is provided to aid in maintaining a substantially constant air pressure in line 186 and for venting air from the cylinders 25 and line 186 to lower the head H. A relatively small air tube 192 is connected to air line 186 and is connected to the pressure operated electrical switch enclosed in the protecting housing 193 and when the air pressure in line 186 exceeds a predetermined value the electrical switch in housing 193 is opened to de-energize the solenoid and to open the valve 191 and vent air to the atmosphere through the vent tube 194. In practice, valve 191 and the switch in housing 193 maintain the pressure in cylinders 25 within 6 oz. per sq. in. of the correct pressure. By means of a manually operable vent tube valve 195 the rate of flow at which the air is exhausted may be readily controlled. When enough air has been exhausted so that the pressure in line 186 is at the desired value, the switch in housing 193 closes and energizes the solenoid valve 191 thereby closing the valve. Valve 185 is normally closed and valve 191 is normally open, thus air pressure can only build up in the cylinders 25 to raise the head when the electrical circuit to these valves is closed to energize the solenoid of each valve.

By means of regulators 179 and the solenoid valve 191 and its control switch in housing 193, the air pressure in cylinders 25 and air line 186 can be maintained within very close limits. When the head H is raised, it is urged upwardly into contact with the bottom surface of slab S with a force only slightly greater than necessary to raise the head, therefore the head will follow and assume a position normal to the bottom surface of warped, twisted and irregular slabs. If the pressure of head H against the slab surface is slight, the heads can readily be forced downward to follow the surface thus preventing or minimizing damage to the head and the wearing away of the nozzle shoe is reduced to a minimum.

To lower the head H, the solenoid valve 185 is deenergized, thus closing the valve to prevent air from entering line 186 from line 183, and the solenoid valve 191 is deenergized to open the valve and vent air through the tube 194 to the atmosphere. The weight of the head H causes the pistons in cylinders 25 to lower. The upper or rod ends of cylinders 25 are open to the atmosphere to prevent the creation of a vacuum or pressure which would interfere with the raising and lowering of the head H. To prevent the upwardly urged head H from lifting the slab S from rollers 20 and more particularly to maintain the slab in contact with the rollers adjacent the head H, a

hold-down roller 196 is pivotally mounted above the slab S and substantially above the head H as shown in Figs. 1 and 4. The roller 196 extends across the slab and may be pivotally supported at each end in vertically slidable blocks 220 mounted in members 188 which may be in turn mounted on each side of the roll table support. The roller 196 is resiliently pressed downward by the springs 221 and holds the slab S in contact with the roll table rollers 20 which are adjacent the head H and maintains the slab in the correct position for desurfacing.

In the frame of a carriage F there are mounted two heavy coil springs 197 each confined within a casing 198 (Figs. 2 and 9). A cap 199 is mounted on top of each coil spring 197 and is slidably confined in the upper end of the casing 198. To the bottom of the carrier plate 23 there are fastened two downwardly depending members 200 and when the head is in the lowered position, each member 200 rests on a corresponding cap 199. Thus, the coil springs 197 resiliently support the head when in the lowered position and act as shock absorbers if the head is lowered suddenly.

As shown in Fig. 1, beneath the conveyor C and the slab S there is pivotally supported in member 202 a horizontal transverse shaft 203 on which there is mounted an arm 204 the outer end of which carries a shoe 205 normally contacting the bottom surface of the slab S. Also on shaft 203 is arm 206 which may be separate from or an extension of arm 204 so that arms 204 and 206 in effect form a bellcrank. The outer end of arm 206 contacts a pressure exerting member, such as a spring contained in member 207, so that shoe 205 is urged upwardly against the slab S. On shaft 203, there is mounted a switch operating arm 208, so positioned that when shaft 203 turns, arm 208 either opens or closes the electric switch 209. When the final or leaving end of slab S passes over the shoe 205, the arm 204 swings upwardly and moves arm 208, thereby operating the switch 209 which is connected in such a manner to the solenoid valves 185 and 191 as to automatically lower the head H. It is preferable that an electrical time delay device be interposed in the electrical circuit of switch 209 so that the head H will not start to lower until the end of the slab is a predetermined distance from the nozzles. The ends of slab S are usually very irregular in shape and are subsequently removed. If such an end should strike the head H, while it was being urged upwardly against the slab, serious damage to the head may result. By correctly positioning the arm 204 and by correctly setting the electrical time delay device, the head H can be lowered far enough away from the slab so as to prevent or minimize any possible damage to the head H, and even though an irregular slab should strike the head, the head would probably not be damaged if moving in a downward direction. When head H starts to lower, the preheating flames and the oxidizing gas are preferably left on for a short length of time which prevents clogging of the nozzles and additionally aids in completely or nearly completely desurfacing the slab.

A shock absorber 212 may be mounted on the roll table frame, or on other suitable means, as shown in Fig. 1. Because of imperfections in the surface of the slab, the friction between the slab S and head H may become great enough to cause the machine to tilt in the direction of slab movement. Additionally, the head H may

be subjected to impact from downwardly turned, trailing slab ends. If such friction or impact is great enough to tilt the machine, an outwardly projecting member 213 which is mounted on the back of the machine contacts the plunger 211 of the shock absorber 212. The plunger 211 may be under spring pressure to lessen the effect of the impact on the head H. A suitable switch may be mounted on the roll table so that, if the machine tilts rearwardly, the member 213 will operate the switch to break the electrical circuit of the roll table motor to stop the movement of the slab, or to break the circuit to the solenoid valves 185 and 191 as shown in Fig. 19 and thereby cause the head to lower, or to do both. Thus, the shock absorber 212 is a safety means for preventing damage to the machine by absorbing the impact of deformed slabs against the head H and by relieving the friction between head H and slab S.

During the desurfacing operation, the oxidizing gas reacts with the surface material of the slab S to produce molten slag mixture which falls away from the bottom surface of the slab in a curved path. A hopper W is provided beneath the conveyor C to collect this molten slag. In the hopper W, a number of water sprays 215 are provided to maintain a film of water on the surface of the sidewalls and the bottom 216 of hopper W. When the molten slag impinges on a wet surface, a blanket of steam is formed between the surface and the slag which prevents the slag from adhering to the surface. Thus, a large part of the molten slag impinges on the hopper wall 214 which acts as a slag shield and the slag falls to the bottom of the hopper either as a solid or as a liquid which is quickly cooled by the water. The slag collects on the bottom 216 of hopper W in the form of porous particles or lumps of solid slag. Streams of water may be directed across the bottom 216 to wash the slag through the opening 217 in the side of the hopper into the chute 218 which may lead to a pit where the slag may be collected in buckets and where the water may enter a drain. The slag, after collection may be reclaimed by smelting in a usual manner. The slag quickly falls away from the bottom surface and does not tend to pile up on the surface and clog the nozzles or flow over the sides to form fins or flow over the trailing end as when desurfacing a top surface. When desurfacing from the bottom the disposal of the slag does not involve the considerable difficulties which are involved in the disposal of the slag which pours over the trailing end when removing metal from a top surface.

It is preferable that this machine be controlled by means of electrical switches located at a remote point such as at a remote control table out of the zone of high temperature heat. A plurality of switches may be sequentially operated to operate this machine but it is preferable that a single sequentially operable switch be used. A sequentially operable drum-type switch similar to that disclosed in the United States application, Serial No. 272,555, filed May 9, 1939 by James H. Bucknam now issued as Patent No. 2,244,822 is suitable for controlling this machine.

Fig. 19 is a wiring diagram schematically illustrating the electrical circuit of the control means for operating this machine. Fig. 20 illustrates the sequential operation of the drum-type switch controller, through the five positions and the "off" position, and along with Fig. 19, illustrates the general operation of this desurfacing ma-

chine. All non-essential elements have been eliminated from Fig. 19 to shown more clearly the essential elements. The drum-type switch controller is provided with eight contacts designated *a1* through *h1*, inclusive, which are all connected to the line *L1* except contact *g1* and which are brought into proper sequential engagement with corresponding contacts *a2* through *h2* to correctly operate the machine.

With the drum-type switch controller in the off position, as shown in Fig. 19, only the contacts *a1*, *a2* and *b1*, *b2* are closed and the operator by means of push button switches *225* and *226* can cause the desurfacing machine to move into or out of alignment with the roll table. A limit switch *229* may be provided in the motor circuit for limiting the inward movement of the machine and a limit switch *230* preferably is provided in the circuit of motor *42* for limiting the outward movement of the machine. When the machine is in the outward position, at one side of the roll table, the limit switch *230* is open and the limit switch *229* is closed so that the operator by actuating the push button switch *225* can complete the electrical circuit from *L1* through line *232* and the carriage motor *42* to *L2* to cause the machine to move inwardly and into alignment with the roll table. This inward movement is limited by the stop *168* and/or the limit switch *229* which when actuated by movement of the machine breaks the motor circuit. When the machine is not in the outward position, the out limit switch *230* is closed and the operator by actuating the push button switch *226* can complete the electrical circuit from *L1* through line *233*, and the motor *42* to *L2*, to cause the machine to move outwardly until stopped by the opening of the limit switch *230*. One or the other of the limit switches *229*, *230* is always in the closed position. A push button switch *235* is preferably provided in the carriage motor circuit so that the circuit can be broken and the machine stopped at any time.

Additionally, when the drum-type switch controller is in the off position, contacts *b1*, *b2* are closed and the separate roll table controlling switch *236* may be operated to selectively cause the roll table motor, indicated at *237*, to rotate in either direction to move the slab *S* either forwardly or rearwardly as may be desired or to move the slab into position for the desurfacing operation to be started. The roll table control switch has forward, reverse and off positions. The contacts *a1*, *a2*, *b1*, *b2* are closed only when the drum-type switch controller is in the off position so that the carriage cannot be moved transversely of the roll table and the slab cannot inadvertently be moved along the roll table when the head *H* is in the raised or operating position, thus preventing damage to the blowpipe head *H*.

With the controller moved to the first position, the contacts *d1*, *d2* are closed to energize the solenoids of the solenoid operated valves *185* and *191* to close the valve *191* and open valve *185* to admit air under pressure into the cylinders *25*, thereby raising the blowpipe head upwardly and into contact with the bottom surface of the slab *S*. The contacts *f1*, *f2* are preferably closed, in which event, the closing of the two limit switches *170* completes the circuit of the solenoid operated valve *158* to automatically turn on the preheat gases before the head contacts the slab. If desirable, the controller may be so constructed as to not close the contacts *f1*, *f2* when in the first position so that the preheat gases are not auto-

matically turned on by movement of the head.

When the controller is moved to the second position the contacts *d1*, *d2* remain closed, the contacts *f1*, *f2* either remain closed or are closed and contacts *g1*, *g2* are preferably closed. With contacts *f1*, *f2* and *g1*, *g2* closed, the circuit of the solenoid operated valve *158* is closed so that the preheat gases are turned on if these gases have not been automatically turned on by the upward movement of the desurfacing head. After a short preheating period to raise a portion of the surface metal to the oxygen ignition temperature the controller is moved to the third position which additionally and simultaneously closes the contacts *c1*, *c2*, and *h1*, *h2* and preferably closes the contacts *e1*, *e2*. With the contacts *c1*, *c2* closed the forward circuit of the roll table motor is completed and the roll table motor is so energized as to move the slab forwardly along the roll table past the desurfacing head. The closing of the contacts *h1*, *h2* energizes the solenoids of the eight solenoid operated valves *123* to turn on the cutting oxygen. The contacts *d1*, *d2* remain closed when the controller is in the third position, and if desirable, the normally closed switch *238* may be provided on the roll table support and interposed in the electrical circuit of valves *185* and *191* so that if friction between the slab and the head causes the machine to tilt, the projecting member *213* will open the normally closed switch *238* and de-energize the solenoids of valves *185*, *191* to cause the head to be lowered. Also, when the controller is moved to the third position the contacts *e1*, *e2* are closed so that the trailing end of the slab *S* by releasing the upwardly urged arm *204* actuates the limit switch *209* to energize the adjustable time delay mechanism *TD*. After a predetermined period has elapsed, the time delay mechanism *TD* energizes the relay *240* to open the normally closed switch *241* to break the electrical circuit of valves *185* and *191*. When the switch *241* is opened by the relay *240* the solenoids of the valves *185* and *191* are de-energized so that air is exhausted from the cylinders *25* to lower the blowpipe head. Preferably, when the controller is in the third position the contacts *f1*, *f2* are closed and the contacts *g1*, *g2* are open so that after the head is lowered a predetermined distance the downward movement of the head actuates the two switches *170* to de-energize the solenoid valve *158* and thereby turn off the preheat gases. If desirable, contacts *g1*, *g2* can be closed when the controller is in the third position so that the downward movement of the blowpipe head does not turn off the preheat gases.

The fourth position is provided on the controller for more particularly causing the blowpipe head to move downwardly so that if for any reason it is not desirable to move the head automatically downwardly through the operation of limit switch *209*, the blowpipe head can be moved downwardly by means of the controller. When the controller is in the fourth position the contacts *d1*, *d2* are open which de-energizes the solenoids of valves *185*, and *191* and preferably the contacts *c1*, *c2* remain closed so that the slab will continue to move in a forward direction along the roll table. Also, if desirable the contacts *f1*, *f2*, and *g1*, *g2* may be kept closed so that the preheat gases are left on and the contacts *h1*, *h2* may be closed to leave on the cutting oxygen.

With the controller in the fifth position all of the contacts are preferably open and the sole-

noid of the preheat valve 188 and the solenoids of the cutting oxygen valves 123 are all de-energized to turn off all of the gases. If desirable the contacts b_1 , b_2 , can be closed by the controller when in the fifth position so that the operator by actuating switch 238 can control the roll table motor to move the slab along the roll table in the desired direction. From the fifth position the controller is moved to the off position and only the contacts a_1 , a_2 and b_1 , b_2 are closed and the operator can, by means of the push button switches 225, and 226, cause the desurfacing machine to move transversely of the roll table and by means of switch 236 can cause movement of the slab along the roll table in the desired direction, all in the manner previously described.

When the slab S is correctly positioned on the roll table C and the surface-conditioning machine is in the operable position beneath the roll table, the control switch may be moved from the "off" position to the first position to energize the solenoid valve 185 thereby moving the head H upwardly and urging it upwardly against the bottom surface of a slab. The upward movement of the head H may operate the switches 170 on columns J and J' to turn on the preheating gases, or, to turn on the preheating gases and either immediately, or after a delay of a predetermined length of time, ignite the gases. If the switches 170 are not employed, the preheating flames may be turned on by moving the drum control switch to the second position. After a short preheating period during which the preheating flames are directed onto a relatively narrow transverse zone extending substantially across the slab and adjacent to the starting end thereof, the control switch may be moved to the next position to turn on the cutting oxygen and simultaneously to start the roll table to move the slab relative to the head H thereby desurfacing the bottom slab surface. As the final end of the slab approaches the head, the arm 204 will be released to operate switch 209 and after a predetermined period has elapsed, solenoid valves 185 and 191 will be de-energized to lower the head. As the head lowers, the preheating flames will be left on until the switches 170 are operated to turn off the preheat gases and, the control switch preferably is not operated immediately so that the oxygen is left on to completely desurface the head. If preferable, the head may be lowered and the preheat gases and the cutting oxygen turned off by moving the control switch through two additional positions as previously described.

After the bottom surface has been desurfaced, the slab may be turned over and run rearwardly along the roll table above the machine until the starting end is reached. The machine then may be operated to remove the defective metal from this second surface as previously described. Instead of making two passes to desurface the top and bottom surfaces, this machine may be used with other machines such as the desurfacing machine described in the copending application, Serial No. 255,398, filed February 9, 1939 by James H. Bucknam, Alfred J. Miller, and Arthur M. Keller now issued as Patent No. 2,200,259 for simultaneously removing defective surface metal from both the top and bottom surfaces at each pass.

Obviously, certain features of this invention may be used independently of others and changes may be made in various parts of the apparatus without departing from the spirit or scope of the invention. For example, although as herein dis-

closed, the apparatus and process are especially adapted for desurfacing semi-finished relatively wide steel slabs while they are at a red heat and in transit between successive rolling operations, it will be understood that the same principles are applicable to the desurfacing of relatively narrow steel billets, blooms, and the like which are cold or at ordinary atmospheric temperature. In addition, this apparatus could be used for directing gases, such as heating flames onto the surface of a body for removing scale therefrom. Furthermore, other types of blowpipes may be employed to progressively apply wide streams of gas obliquely against and lengthwise of the longitudinal surfaces undergoing treatment.

What is claimed is:

1. In apparatus for conditioning the bottom surface of an elongated metal body such as a steel slab, a roll table for supporting and moving said slab, and a blowpipe machine disposed completely below said slab and said roll table and including a frame; a blowpipe head adapted to project a substantially sheet-like stream of gas against the bottom surface of said slab; and pneumatic raising and lowering means for supporting substantially the entire weight of said head on said frame and for urging said head upwardly against said surface.
2. Apparatus for thermally conditioning the surface of a metal body such as a steel slab comprising, in combination, a blowpipe head adapted to project gas against a surface of such a body; means for supporting said slab in a position for surface treatment; a frame for supporting said head; at least one cylinder adapted to raise and lower said head and for urging said head against said slab with a substantially definite predetermined force; and means for supplying gas at a substantially exact predetermined pressure to said cylinder, said means including a source of gas supply under pressure, a tank adapted to maintain a relatively large volume of gas therein, a valve for controlling the flow of gas from said source and said tank to said cylinder, and a relief valve for automatically venting gas from said cylinder and said tank when the pressure in said cylinder exceeds said predetermined pressure.
3. Apparatus for surface conditioning a metal body such as a steel slab comprising a blowpipe head adapted to project a stream of gas against a surface of said slab; a frame; raising and lowering means for supporting said head on said frame and adjacent and in sliding contact with said surface; power-actuated means for supporting said slab in a position for surface treatment and for moving said slab relative to said head, said head being so supported that excessive friction between said head and said slab may move said head in the direction of said slab movement; and, a mechanism operable by movement of the head in the direction of said slab movement for automatically relieving the friction between said head and said slab.
4. Apparatus for conditioning the surface of a metal body such as a steel slab comprising a blowpipe machine including a blowpipe head adapted to project a substantially sheet-like stream of gas against a surface of said slab, and raising and lowering means for supporting said head adjacent said surface; means for moving said slab relative to said machine; and a switch mechanism operable by relative movement past the final end of said slab for automatically initiating movement of

said head away from said surface before said final end reaches said head.

5. In apparatus for thermally conditioning the surface of a ferrous metal body such as a steel slab, a blowpipe head having nozzle means adapted to project gas against the bottom surface of such a body, the head being of sufficient width to project gas on a narrow transverse zone of said surface extending substantially completely across said surface; means for supporting said slab above said head in a position for surface treatment; means for effecting relative movement of said slab and said head; a frame for supporting said head; raising and lowering means for supporting said head on said frame and for urging said head upwardly against said slab with a force in excess of the weight of the head; and switch means for automatically turning on the gas flow before said head contacts said slab to purge the nozzles and gas supply lines thereby reducing the tendency for backfiring.

6. In apparatus for thermally conditioning the surface of a ferrous metal body such as a steel slab, a blowpipe head having nozzle means adapted to project gas against the bottom surface of such a body, the head being of sufficient width to project gas on a narrow transverse zone of said surface extending substantially completely across said surface; means for supporting said slab above said head in a position for surface treatment; means for effecting relative movement of said slab and said head; a frame for supporting said head; raising and lowering means for supporting said head on said frame and for urging said head upwardly against said slab with a force in excess of the weight of the head; and switch means for automatically shutting off the gas flow only after the head has been lowered a predetermined distance from said surface thereby preventing slag from adhering to the outlet ends of said nozzle means.

7. In apparatus for thermally conditioning the surface of a metal body such as a steel slab, a blowpipe head having nozzle means adapted to project gas against the bottom surface of such a body, the head being of sufficient width to project gas on a narrow transverse zone of said surface extending completely across the surface; means for supporting said slab above said head in a position for surface treatment; means for effecting relative movement of said slab and said head; a frame for supporting said head; raising and lowering means for supporting said head on said frame and for urging said head upwardly against said slab with a force in excess of the weight of the head; a hold-down roll supported above the slab to urge said slab downwardly and into contact with the rollers adjacent said head; and means for adjusting the force with which said roll urges said slab downwardly.

8. In apparatus for thermally conditioning the surface of a ferrous metal body such as a steel slab, a blowpipe head having nozzle means adapted to project gas against the bottom surface of such a body, the head being of sufficient width to project gas on a narrow transverse zone of said surface extending substantially completely across said surface; means for supporting said slab above said head in a position for surface treatment; means for effecting relative movement of said slab and said head; a frame for supporting said head; raising and lowering means for supporting said head on said frame and for urging said head upwardly against said slab with a force in excess of the weight of the head; switch

means operable upon the relative movement of the final slab end past such switch means for initiating the downward movement of said head away from said surface before said final end contacts said head.

9. In apparatus for thermally conditioning a surface of a metal body such as a steel slab, a blowpipe head having nozzle means adapted to project gas against a surface of such body; means for supporting said slab in a position for surfacing treatment; a frame for supporting said head; means for effecting relative movement of said slab past said head; raising and lowering mechanism for supporting said head on said frame; and, means for automatically shutting off the gas flow to said head only after the head has been moved a predetermined distance from said surface, thereby preventing slag from adhering to the outlet ends of said nozzle means.

10. Apparatus for thermally conditioning the surface of a metal body such as a steel slab comprising, in combination, a blowpipe head having nozzle means adapted to project gas against the bottom surface of said body, said head being of sufficient width to project gas against a zone of said surface extending completely across the surface, and, said head comprising a row of header blocks each carrying a row of nozzles and a nozzle shoe removably attached to each of said blocks and completely enclosing the nozzles except the orifice ends thereof; a conveyor for supporting said slab above said head in a position for surface treatment and for moving said slab relatively with respect to said head; a frame; column means on said frame for separately guiding each lateral end of said head, said guiding means being constructed and arranged to confine movement of said head in a plane transversely of said body and normal to said surface; a pair of air cylinders rockably mounted on said frame and connected to said head for raising and lowering said head; switch means operable by vertical movement of said head for automatically turning on the gas flow before said head rises into contact with said slab and for automatically shutting off the gas flow after said head has been lowered a predetermined distance from said slab; switch means operable by the movement of the final end of said slab past said switch for initiating downward movement of said head away from said surface; and, means for deflecting and collecting slag produced during the desurfacing operation.

11. In a machine for thermally conditioning the surface of a ferrous metal body such as a steel slab, a blowpipe head adapted to project gas against the bottom surface of said slab, the width of said head being sufficient to project gas on a narrow transverse zone of said surface extending completely across said bottom surface; a supporting frame; guiding means on said frame for separately guiding each lateral end of said head; and raising and lowering means mounted on said frame and connected to said blowpipe head for moving and urging said head upwardly against said slab with a force slightly greater than necessary to overcome the weight of said blowpipe head.

12. In a machine for thermally conditioning the surface of a ferrous metal body such as a steel slab, a blowpipe head adapted to project gas against the bottom surface of said slab; the width of said head being sufficient to project gas on a narrow transverse zone of said surface extending substantially completely across said bottom surface; a supporting frame; guiding means on said

frame for separately guiding each lateral end of said head; and raising and lowering means including two air cylinders rockably mounted on said frame, piston rods extending upwardly from said cylinders, means rockably connecting said piston rods to said head, and means for simultaneously supplying air at equal pressure to both of said cylinders for moving and urging said blowpipe head upwardly against said slab with a force slightly greater than necessary to overcome the weight of said blowpipe head.

13. A machine as claimed in claim 11, which includes switch means operable by the upward movement of said head for turning on the gas flow before said head reaches said surface.

14. A machine as claimed in claim 11, which includes switch means operable by the downward movement of said head for shutting off the flow of gas to said head when said head has been lowered a predetermined distance from said surface.

15. In a machine for thermally conditioning the surface of a ferrous metal body such as a steel slab, a blowpipe head adapted to project oxidizing gas against the bottom surface of said slab, the width of said head being sufficient to project gas on a narrow transverse zone of said surface extending completely across said surface; a supporting frame; guiding means on said frame for separately guiding each lateral end of said head, said guiding means being constructed and arranged to confine the movement of said head in a plane transversely of said body and normal to said surface; and two air cylinders mounted in said frame and connected to said head for raising and lowering said head toward and away from said surface said air cylinders being connected and arranged to permit lateral canting of said head.

16. A machine as claimed in claim 15 which includes pressure control means for automatically controlling the pressure of the air supplied to said cylinders within narrow limits for providing a constant upward force exerted by said air cylinders in excess of the weight supported by a constant amount.

17. A process for surface conditioning a metal body such as a steel slab, comprising heating at least a portion of the surface metal to be removed to the ignition temperature; directing by suitable means a stream of oxidizing gas obliquely against and along a surface of said slab for removing surface metal therefrom; moving said gas applying means relatively along said surface; moving

said gas applying means away from said surface before the end of said slab is reached; and continuing the flow of gas therefrom for a short time to prevent slag adherence thereto and to finish 5 conditioning said surface.

18. A process for conditioning the entire bottom surface of an elongated metal body such as a steel slab in a single pass, comprising heating at least a portion of the surface metal to be removed to the 10 ignition temperature; directing by suitable means a substantially sheet-like stream of gas obliquely against the bottom surface of said slab for removing surface metal therefrom; moving said gas applying means relatively along said surface; 15 moving the gas applying means away from said surface before the end of said slab is reached and continuing the flow of gas therefrom for a short time to prevent slag adherence thereto.

19. In apparatus for surface conditioning a 20 ferrous metal body, a head adapted to project a stream of gas against a surface of such a body; raising and lowering means for supporting said head and for moving said head toward and away from said body; means for effecting relative 25 movement between said head and said body longitudinally along said body; and means including a time delay mechanism for automatically initiating movement of said head away from said body when said head is a predetermined distance from 30 the end of said body thereby substantially completely conditioning said surface and preventing damage to said head.

20. In apparatus for thermochemically conditioning a ferrous metal body such as a steel slab, 35 a blowpipe head adapted to apply gas against a surface of said slab; a frame for supporting said head; raising and lowering mechanism for supporting said head on said frame; means for effecting relative movement between said head and 40 said body; control means operably connected to said raising and lowering mechanism and including an adjustable time delay mechanism and switch means operable by relative movement of the final slab end, said time delay and said switch 45 means being so constructed and arranged that movement of said head away from said surface is initiated when said slab end is a predetermined distance from said head thereby substantially completely conditioning said surface and preventing 50 damage to said head.
